Primary Examiner — David Muller*Assistant Examiner* — Nathan Johnston(74) *Attorney, Agent, or Firm* — Gardner Groff Greenwald & Villanueva, PC(57) **CLAIM**

The ornamental design for fluid transfer lid, as shown and described.

DESCRIPTION

FIG. 1 is a first perspective view of a fluid transfer lid showing our new design.

FIG. 2 is a second perspective view thereof.

FIG. 3 is a left side elevation view thereof.

FIG. 4 is a right side elevation view thereof.

FIG. 5 is a front elevation view thereof (the rear elevation view being a mirror image thereof).

FIG. 6 is a top plan view thereof.

FIG. 7 is a bottom plan view thereof; and,

FIG. 8 is a cross-sectional view along the longitudinal axis shown in FIG. 6.

The broken line showing of fluid transfer lid is included for the purpose of illustrating portions of the "article" and forms no part of the claimed design.

1 Claim, 3 Drawing Sheets(56)
